UNITED STATES PATENT OFFICE

2,512,198

AIR COOLER

Mead B. Davidson, Dallas, Tex.

Application June 17, 1946, Serial No. 677,255

1 Claim. (Cl. 62—134)

1

This invention relates to air conditioning units and more particularly to air conditioning units for use in vehicles.

The objects of the invention are, first, to provide an air conditioning unit so constructed as to be capable of reducing the temperature within the confines of a vehicle; second, to provide an air conditioning unit so constructed that it will require only a small space for mounting in the vehicle.

Another object of the invention is to provide an air conditioning unit adequately insulated against the influence of outside temperatures upon the cooling element within the unit.

Still another object of the invention is to provide an air conditioning unit having therein baffle plates so arranged and spaced that the enforced circuitous route of the air being forced through the unit will provide a prolonged period of cooling said air thus insuring the maximum results.

Still another object of the invention is to provide an air conditioning unit for vehicles which lends itself to both cooling and heating the interior of a vehicle.

With the foregoing objects as paramount, the invention has further reference to certain features of accomplishment which will become apparent as the description proceeds, taken in connection with the accompanying drawings wherein:

Figure 1 is a cut-away perspective view of an air conditioning unit constructed according to the invention.

Figure 2 is a partial side elevation in fragmentary section of an air conditioning unit constructed according to the invention.

Figure 3 is a rear elevation in fragmentary section of an air conditioning unit constructed according to the invention, and

Figure 4 is a plan view of a modified form of the invention with top removed to show diagrammatically the heating coil therein.

Continuing with a more detailed description of the drawings, reference numeral 10 denotes the box or container of the air conditioning unit, said box or container having double walls and a double bottom and a removable cover or top 11. The inner walls and bottom of the box 10 define a compartment 12 for receiving ice or comparable cooling elements. As insurance against the influences of outside temperatures upon the ice in the compartment 12, the cover 11 is insulated as indicated by 13 in Figures 1 and 3.

Upon the back end of the container 10 is 55 meaning of the appended claim is also considered

2

mounted, by suitable means, a fan 14 for forcing air into, through and out of the unit. Between the double walls and double bottom of the box 10 are spaced baffle plates 15, the vertical baffle plates extending alternately upwardly from the bottom and downwardly from the top but in each case just a little short of extending the full distance from bottom to top and from top to bottom. All baffle plates are fixedly attached to the inner and outer walls and bottoms. The obvious purpose of the baffle plates 15 being to cause the air, being forced through the unit by the fan 14, to take a longer, more circuitous route through the unit thus prolonging the period of cooling before reaching a point of egress at 16.

Upon the opposite end of that to which the fan 14 is mounted, and covering the air exit 16, is suitably mounted a manifold 17 for diverting the flow of air into a hose 18 joined to the manifold 17 by suitable means at 17a. Upon the other end of the hose 18 is attached an element 19 having therein a multiplicity of small apertures 20 for diffusion of the out-pouring air. Since the hose 18 is flexible and may be of any length desired the diffusion element 19 may be placed, at will, anywhere within the vehicle.

In the bottom of the air conditioning unit and extending from the ice compartment 12 downwardly through and outside of the lower bottom 30 of the box 10 is a tubular aperture 21 for draining said ice compartment. Integrally formed in the tubular aperture 21 are apertures 21a for draining the sections between the double walls and double bottom of the container 10. To the outer end of the tubular aperture 21 is attached a flexible hose 22 for directing the flow of melted ice as may be desired. The bottom of the compartment 12 has corrugations a as a measure to hold ice blocks against movement when the vehicle is in motion.

In Figure 4 is shown a plan view of a modified form of the invention in which the chamber or compartment 12, serves as heating instead of a cooling chamber. Heating coils 23 are extended longitudinally in the chamber 12 and insulated at 24. A heating circuit 25 energizes the coils 23 and it is obvious that air circulated between the walls of the unit will be influenced to higher temperatures upon contact with the inner wall defining the chamber 12.

Manifestly, the construction of such an air conditioning unit as shown and described is capable of some modification and such modification as may be construed to fall within the scope and

to be within the spirit and intent of the invention.

What is claimed is:

In an air conditioning unit for vehicles, the combination comprising a box having an insulated and removable top, a fan mounted over an opening in one end of said box for forcing air therethrough, an ice compartment within said box, vertically and horizontally staggered baffle plates mounted between the walls and bottom of said box and ice compartment to hold the walls of the latter in spaced relationship with those of said box and for constraining air passing therethrough to travel in a circuitous course to prolong the cooling period of said air, an air outlet in the end of said box opposite said fan, a flexible hose connected to said outlet at one end and means

at the other end of said hose for diffusing said air and a common means for draining said unit interiorly and exteriorly of said ice chamber.

MEAD B. DAVIDSON.
